UNITED STATES PATENT OFFICE.

HOWARD R. SARGENT, OF SCHENECTADY, NEW YORK, ASSIGNOR TO
GENERAL ELECTRIC COMPANY, A CORPORATION OF NEW YORK.

ARC-LAMP HANGER.

SPECIFICATION forming part of Letters Patent No. 755,797, dated March 29, 1904.

Application filed September 2, 1902. Serial No. 121,731. (No model.)

To all whom it may concern:

Be it known that I, HOWARD R. SARGENT, a citizen of the United States, residing at Schenectady, county of Schenectady, State of New York, have invented certain new and useful Improvements in Arc-Lamp Hangers, of which the following is a specification.

This invention relates to electric lighting; and its object is to enable an arc-lamp to be automatically attached to and detached from a support by simply pulling on the cord by which it is raised and lowered. The device is so arranged that when the lamp is detached from the support a cut-out switch will be automatically closed to preserve the electrical continuity of the line. I attain these results by means of an improved hanger consisting of two separable portions, one suspended from a guy-wire or other support and the other attached to the lamp. The latter is provided with a cam groove or shoulder which when said portion is raised by the cord fastened thereto will engage with a pin in the upper portion and automatically guide said pin into a notch, so that the lower portion will be suspended from the upper portion and the strain will be removed from the cord. Moreover, when the two portions are brought into engaging relation certain contacts on each portion are automatically brought to the proper position for making the desired circuit connections between the lamp and the line. By renewing the pull on the cord the two portions will be disengaged, so that the lamp can be lowered.

In the accompanying drawings, Figure 1 is a central longitudinal section, partly in elevation, of my improved hanger, taken on the lines 1 1, Figs. 2 and 4. Fig. 2 is a bottom plan view of the upper portion. Fig. 3 is a top plan view of the lower portion. Fig. 4 is a side elevation, partly broken away. Fig. 5 is a side elevation of a lamp equipped with my hanger, and Fig. 6 is a development of the cams and notches on the upper end of the attaching-plug.

The hanger comprises a pendant 1, having an eye 2 to slide on or be suspended by a wire or rod 3 and serving as a housing for a pulley

4, over which runs a cord 5 for raising and 50 lowering the lamp 6. The end of the cord is secured in a tubular plug 7, into the lower end of which is screwed the hook 8, on which the lamp is hung. Attached to or integral with the pendant 1 is a socket 9, into which 55 the plug enters when the lamp is raised. The plug and socket are provided with means for automatically fastening and unfastening them by simply pulling on the cord 5. The means I prefer comprises a pin 10, projecting radially into the socket from one side thereof and coöperating with a cam-shoulder 11 on the plug. Said shoulder encircles the plug obliquely, terminating at one end in a tongue 12, standing at a higher point on the plug than 65 the other end of said shoulder, which runs into a notch 13 a little beyond the tip of the tongue. The under side of the tongue runs up obliquely to a notch 14, then downwardly to a notch 15, and then up longitudinally of 70 the plug. The shoulder 11 after passing the notch 13 runs nearly parallel with the under side of the tongue, forming with it a W-shaped groove. The operation of these parts is as follows: When the lamp is raised by the cord, 75 the plug enters the socket, and as soon as the shoulder strikes the pin the plug is partially rotated until as the shoulder slides past the pin the notch 13 is brought up against the pin and the upward movement of the plug is 80 checked. The cord is then slackened away and the under side of the tongue 12 comes in contact with the pin, causing the plug to rotate still further until the pin comes into the notch 14, where it arrests the motion of the plug 85 both angularly and longitudinally. The lamp is thus suspended on the pin. To lower it, the cord is pulled again, raising the plug until the notch 15 comes against it, whereupon by slackening off the cord the plug and the lamp 90 will drop, the pin passing up through the vertical part of the slot.

The line-terminals are connected with two metallic ears 16 17, secured to an annular block 18, of insulation, attached to and concentric with the socket 9. From the ear 16 extends a spring-arm 19, carrying a contact 20, the other ear having a similar spring-arm 19'

and contact 20'. The two contacts press against each other and keep the main line closed when the lamp is lowered out of the hanger. The lamp-terminals are connected with two metallic ears 21 22, secured to an annular block 23 of insulation attached to and concentric with the plug 7. The ear 21 carries a spring-contact 24, adapted to slide under and lift the upper spring-arm 19 when the lamp is raised into the hanger. The other ear has a spring-contact 25, adapted to make contact with a similar spring 26, connected with the ear 17. When the lamp is pulled up into place, the line-circuit is broken at the contacts 20 20' and the lamp-terminals are put in connection with the line-terminals by means of the springs 19 24 and 25 26. The contacts are protected from the weather and from dust by a petticoat 27, depending from the base of the socket.

What I claim as new, and desire to secure by Letters Patent of the United States, is—

1. An arc-lamp hanger comprising a socket and a freely-rotatable plug, and means for automatically alining the respective parts and engaging them when the plug passes up into the socket and for disengaging them by a slight upward movement of the plug.

2. An arc-lamp hanger comprising a socket containing a pin, and a freely-rotatable plug having a cam-shoulder and notches to engage with said pin, whereby the respective parts may be alined and the plug can be attached to and detached from the socket by successive upward movements.

3. The combination with a socket having a pin projecting radially into it, of a plug having a cam-shoulder adapted to engage with said pin and thereby aline the respective parts and hold the plug in engagement with the socket.

4. The combination with a socket having a pin projecting radially into it, of a plug having an oblique shoulder running down into a

notch, then upwardly and downwardly into a second notch, and then up longitudinally of the plug, and a tongue extending over the first notch and having its under side running up to a notch and then downwardly and again upwardly, whereby said pin will be guided from notch to notch as it slides along the shoulder.

5. The combination with a pendant, of a pulley housed therein, a socket depending from said pendant and carrying a pin, a tubular plug entering said socket, a cord passing over said pulley and secured in said plug, and cam-shoulders and notches on the plug inter-operating with the pin in the socket to successively engage and disengage the plug and socket when the cord is pulled.

6. In an arc-lamp hanger, the combination with a socket, of line-terminals carried thereby, means for automatically connecting said terminals when no lamp is attached to the socket, a freely-rotatable plug attached to the lamp and adapted to enter said socket, lamp-terminals carried by said plug, and means for automatically alining the respective parts and disconnecting the line-terminals and connecting them with the lamp-terminals when the plug is inserted in the socket.

7. In an arc-lamp hanger, the combination with a socket, of an annular block of insulation concentric therewith, line-terminals on said block, spring-arms normally connecting said terminals, a plug attached to the lamp and adapted to enter said socket, an annular block of insulation concentric with said plug, lamp-terminals on said last-named block, and spring-contacts connected with said lamp-terminals and making contact with the line-terminals when the plug is inserted in the socket.

In witness whereof I have hereunto set my hand this 29th day of August, 1902.

HOWARD R. SARGENT.
